UNITED STATES PATENT OFFICE.

EDWARD J. RICHMOND, OF CARTHAGE, MISSOURI, ASSIGNOR TO DWIGHT J. BLISS, OF SAME PLACE.

LOCKING-HOOK FOR MINERS' BUCKETS.

SPECIFICATION forming part of Letters Patent No. 643,534, dated February 13, 1900.

Application filed August 18, 1899. Serial No. 727,726. (No model.)

To all whom it may concern:

Be it known that I, EDWARD J. RICHMOND, a citizen of the United States, residing at Carthage, in the county of Jasper and State 5 of Missouri, have invented certain new and useful Improvements in Automatic Locking-Hooks for Miners' Buckets; and I do declare the following to be a full, clear, and exact description of the invention, such as will enable 10 others skilled in the art to which it appertains to make and use the same.

My invention relates to improvements in self-locking hooks for miners' buckets; and the object is to provide a simple and effective 15 safety device of this character.

To this end the invention consists in the construction, combination, and arrangement of the several parts of the device, as will be hereinafter more fully described, and particularly pointed out in the claims.

In the accompanying drawings the same reference characters indicate the same parts of the invention.

Figure 1 is a perspective view of my improved self-locking safety-hook. Fig. 2 is a longitudinal section with the locking-tongue raised. Fig. 3 is a similar view with the tongue closed and the bucket-bail shown in dotted lines. Fig. 4 shows a simple manner 25 of connecting the socket with a bucket-bail. Fig. 5 is a modified form of hook. Fig. 6 shows the manner of attaching the rope direct to the hook without the intervention of the swivel. Fig. 7 shows another form of 30 cross-head provided with a ball-bearing sleeve. Fig. 8 is a vertical section of the same. Fig. 9 is a detail view of the sleeve or spool. Fig. 10 is a detail view of the cross-head cast in one piece.

1 denotes a cross-head or socket consisting of two counterpart yokes 1' 1', the meeting faces of which form a recess to receive the swivel-eye-bolt 2.

3 and 4 represent the diverging arms, which 45 encompass and are permanently fixed to the yokes 1' 1' by the transverse rivets 2' 2'.

5 denotes the latch pivoted on the rivet 5' in the lower end of the arm 3, the tongue 6 of the latch passing through the lower end 50 of the arm 4 and resting on the bar 10. As shown in Fig. 3, the face of this tongue 6 is

curved at 8 to engage the correspondingly-curved meeting face 9 of the bar 10, so that when the weight of the bucket is on the latch any tendency of the arms to separate is obviated.

12 denotes a thumb-plate formed integral with the latch 5 and in addition to serving as a guard to limit the upward movement of the tongue by its coming in contact with the end 60 of the arm 4 also acts as a guard to facilitate the entrance of the bucket-bail into the socket, and by acting as a counterbalance to restore said tongue to its locking position it also serves as a convenient medium for expeditiously manipulating said tongue.

13 denotes the bucket-bail, (shown in dotted lines in Fig. 3,) and to release said bail the socket is pressed down and the tongue is raised to the position shown in Fig. 2, which 70 is very simply and conveniently accomplished by means of the thumb-plate. The socket is then clear of the bail and the tongue allowed to drop to its normal position.

A very simple and expeditious manner of 75 connecting the device with a bucket-bail will be understood by reference to Fig. 4, the hook or socket being swung in the direction of the arrow until the thumb-plate meets the bail, at which point the hook is depressed 80 until the tongue contacts with the bail, rising past it, and then falling back by gravity under it to secure the bail in place.

Referring now to Fig. 5, the cross-head is made in two pieces, as before; but the eye 85 2^b in the swivel-bolt 2^a is formed horizontal, so that the end of the rope may be passed through it and knotted to secure it in place.

In Fig. 6 the eyebolt is dispensed with entirely and the end of the rope passed through 90 the cross-head and knotted, as shown.

In Figs. 7 and 8 I have dispensed with the eyebolt and in lieu thereof substituted a sleeve 14, the upper end of which is formed with a guard-collar 15 and the lower end with 95 a heavier bearing-flange 16, the upper face of which is formed with a ball-race 17, in which are mounted the bearing-balls 18. In this instance the end of the wire cable 19 is leaded in the usual manner in the sleeve to 100 secure it in place.

In Fig. 10 I have shown the cross-head

made in one piece and the orifice much enlarged to receive a heavy hemp or manila rope, which is passed through and knotted in the usual manner to retain it in place.

5 It will of course be understood that various changes in the form, proportion, and the minor details of construction may be resorted to without departing from the principle or sacrificing any of the advantages of this invention.

Having thus fully described my invention, what I claim as new and useful, and desire to secure by Letters Patent of the United States, is—

10 15 1. In a safety bail-hook, a swiveled socket formed with diverging arms, a latch fulcrumed in one arm and having its free end

adapted to engage the opposite arm to lock it with reference to the latch-arm, substantially as and for the purpose set forth. 20

2. In a safety bucket-bail hook, a swiveled socket formed with the bifurcated arm 3, and slotted arm 4; in combination with the right-angled latch 5, the outer end of the tongue 6 of which is recessed to engage slotted arm, 25 substantially as and for the purpose set forth.

In testimony whereof I have hereunto set my hand in presence of two subscribing witnesses.

EDWARD J. RICHMOND.
